his attorney

UNITED STATES PATENT OFFICE.

JOHN W. SHELBYNE, OF HANNIBAL, MISSOURI.

PIPE-CLEANING TOOL.

Application filed April 17, 1922. Serial No. 554,351.

To all whom it may concern:

Be it known that I, JOHN W. SHELBYNE, a citizen of the United States, and resident of Hannibal, county of Marion, and State of Missouri, have invented certain new and useful Improvements in Pipe-Cleaning Tools, of which the following is a specification, and which are illustrated in the accompanying drawings, forming a part thereof.

10 The invention relates to an improved form of cleaning tool, and has as its object to provide a flexible bit or shaft which shall serve as an oil tube or other pipe cleaner, and may be used for boring through crooked tubes such as are found in the lubricating systems of automobile engines. The improved drill is adapted to open up such a pipe and free it from the sediment or worn particles from the transmission bands which 15 are so disastrous to the life of the motor.

An illustrative embodiment of the invention is shown in the accompanying drawings, in which—

Fig. 1 is a side elevation of an automobile engine of common construction, a portion of its casing being broken away to show an oil tube of its lubricating system, to which the improved drill is applied for the purpose of cleaning the same;

20 Fig. 2 is a central longitudinal section through the brace which forms the container for the flexible shaft or drill;

Fig. 3 is a section on the line 3—3 of Fig. 2, the bit adjusting device being shown in elevation;

Fig. 4 is a detail longitudinal section on the line 4—4 of Fig. 3; and

Fig. 5 shows the improved bit removed from the brace.

40 The oil tube cleaner comprises an elongated flexible drill or bit 10, which is capable of passing through curved passages, and is preferably formed of a long tightly coiled spiral spring, its free end 11 being sharpened. A hollow brace 12 forms a container for the flexible drill 10.

The brace 12 is shown as provided with the usual handle 25, and is outwardly curved, as at 26, adjacent its upper end, thus providing the usual operating grip. The flexible bit 10 may extend through the curved portion 26 of the hollow container and through a central bore 27 in the handle 25,

one end of the bit being adapted to project 55 beyond the handle 25 and its opposite end beyond the lower end of the brace.

While the portion of the bit which extends beyond the brace may be varied as the operator may desire, by simply pulling the bit 60 in one direction or the other through the container, according to the preferred embodiment of my invention, a bit adjusting device is provided comprising a pair of gripping members or jaws 29, 30, which are firmly 65 held upon a sleeve 31 fitting over the brace 12 by means of a spiral spring 37, which fits over the rear ends of the gripping members. As shown, the brace 12 is provided with a pair of oppositely positioned longitudinal slots 32, 33, through which the front ends 70 of the jaws 29 and 30 project. Each jaw may be provided with a lug 34, which is adapted to fit within a corresponding groove in the sleeve 31, and with points 35, 36, which are adapted to project into the slots 32, 33, and thereby limit the sliding movement of the sleeve 31.

75 The spring 37 is adapted to hold the front points 36 normally out of engagement with the coils of the spiral bit 10. The bit is adjusted by applying pressure to the jaws and moving the same in a forward or rearward direction, as desired. In this manner the bit may be pushed down through a tube until 80 it reaches the obstruction therein. The bit may then be held in its adjusted position by any suitable means, as by a chuck 13 of ordinary construction. When so secured the device is used as a drill.

85 The uses of the device are many. It is particularly useful for cleaning the crooked oil pipes of the lubricating system of an internal combustion engine. In Fig. 1 the outer casing of such an engine is designated generally by the reference numeral 15. The casing is partly broken away, thereby disclosing an oil tube 16, having a collecting funnel 17. By drilling a hole 18 in the casing 15 directly over and a little in rear of the collecting funnel 17 the drill 10 may be 90 inserted in the tube 16.

100 The operation of the device is the same as that of the usual auger or drill. On turning the brace 12 the special bit 10 bores its way through the tube 16, thus opening it up and forcing any sediment which may have ac-

cumulated therein through the end of the pipe opposite the funnel 17, as shown at 20 in Fig. 1.

The tube 16 is shown as bent at 19, but owing to the flexible construction of the drill the bend interposes no obstacle in the way of the cleaning operation.

In practice a small cap or cover is normally placed over the hole 18 in the engine 10 casing to prevent access of dust or other foreign matter. This cap may be readily removed and the tube cleaned in a few minutes. The usual method of cleaning the tube is to remove the transmission cover, which requires a mechanic's labor for a period of 15 several hours.

While the cleaner has been particularly described with reference to its use with an internal combustion engine, it is evident that 20 it may be employed for many other purposes without departing from the scope of the present invention.

I claim as my invention—

1. A pipe cleaning tool comprising a brace 25 having an offset portion between its ends for forming a crank for rotating the same, said brace being provided with a bore extending

through said brace from end to end thereof, a flexible bit slidably mounted in said bore, and means for adjustably holding said bit 30 within said brace.

2. A pipe cleaning device comprising a brace provided with an aperture, a flexible bit slidably mounted in said aperture, and reciprocating means mounted on said brace 35 for adjusting said bit relatively to said brace.

3. A pipe cleaning device comprising a brace, a flexible bit slidably mounted on said brace, reciprocating means for adjusting said bit along said brace, and means for holding 40 said bit in adjusted position on said brace.

4. A pipe cleaning tool comprising a flexible bit, a hollow brace for operating the same 45 through which the bit extends, said brace having a pair of longitudinal slots therein, a sleeve fitting said brace, a pair of jaws hingedly secured to said sleeve and having points projecting into said slots for engagement with said bit, and means for securing said bit in longitudinally adjusted position 50 with respect to said brace.

JOHN W. SHELBYNE.
